Application March 26, 1947, Serial No. 737,380

9 Claims. (Cl. 123—103)

1

The present invention relates to governors for regulating or limiting the speed of internal combustion engines.

An object of the invention is to provide an improved fluid-pressure-operable engine governor which shall afford good speed regulation under different load conditions, and which is particularly suitable for vehicle engines, although not limited to such use.

Another object is to provide an engine governor which is controlled conjointly by intake manifold pressure and by a fluid pressure developed in accordance with engine speed.

Still another object is to provide a governor in which both fluid pressures act on the same diaphragm or similar actuator for controlling a governor valve.

A further object is to provide a simple and durable engine governor which is reliable in operation and which will deter tampering.

A still further object is to provide a governor having a spring unit which is capable of easy assembly and replacement and which will facilitate speed adjustment.

The invention further consists in the several features hereinafter described and claimed.

In the accompanying drawings, illustrating certain embodiments of the invention,

Fig. 1 is a side elevational view of an engine governor constructed in accordance with the invention, parts being shown in section, and a governor valve being shown in full lines in a position assumed when the engine is at rest;

Fig. 2 is a sectional view taken generally on the line 2—2 of Fig. 1, the governor valve being shown in its fully open position;

Fig. 3 is a sectional view of a hydraulic pressure generator, taken generally on the line 3—3 of Fig. 1;

Fig. 4 is a detail longitudinal sectional view of a compound spring unit;

Fig. 5 is a sectional elevational view taken generally on the line 5—5 of Fig. 2, the governor valve being shown in partially closed position assumed when the engine is running under light load at governed speed, and

Fig. 6 is a view similar to Fig. 2, but showing a modified form of governor.

Referring to Figs. 1 to 5, 10 designates the intake manifold of an internal combustion engine of conventional throttling type. The manifold has a riser 11 connected to a downdraft carburetor 12, the latter having the usual throttle valve 13 mounted on a shaft 14. In the case of a vehicle engine, the shaft is controlled through a

lever arm 15 from a foot accelerator or similar actuating means, not shown, which normally controls the flow of the fuel charge into the intake manifold.

6 A fluid pressure generator or pump, designated generally by the numeral 16, is suitably driven by the engine and develops a pressure which varies with engine speed, as hereinafter described. In some instances, the pressure generator may be driven by the vehicle. The pump comprises a reservoir-forming casing 17 to one end of which is secured a hubbed cover or end bell 18 having a substantially horizontal axis. A suitably sealed impeller shaft 19 is journaled in the cover in ball bearings 20 and carries a pulley 21 by which it may be driven, as by the engine fan belt or generator belt, not shown. In some instances, a gear drive, not shown, may be provided. The inner end of the shaft carries an impeller 22, such as a two-lobed type, which rotates in either direction in an impeller chamber 23 formed between the cover and a flat end wall 24 of the casing 17, this wall having a central opening 25 to admit oil or other suitable liquid from the casing into the impeller chamber. The casing is provided at its top with a radial outlet 26 from the impeller chamber, and is also provided at the top of the reservoir portion with a suitable breather 27. The outlet 26 is connected by a tube or conduit 28 to a diaphragm housing indicated generally by 29.

10 With the construction above described, the pump shaft 19 is driven at a speed directly proportional to the speed of the engine, and consequently the pump will develop a pressure in the conduit 28 and diaphragm housing 29 which is a direct function of engine speed.

15 Interposed between the outlet of the carburetor 12 and the intake manifold riser 11 is a throttle body or casing 30 secured in place by bolts 31 and having a vertical through passage 32 for the fuel charge. A throttle shaft 33 extends transversely of the casing 30 and is journaled therein, as by needle bearings 34, the projecting end of the shaft having a gear or pinion 35. A throttle disk 36 is secured to the shaft 33, as by screws 37, and forms therewith a butterfly valve which is disposed below the conventional throttle valve 13, as seen in Fig. 1. The governor valve is of the balanced type, that is, it extends equally on opposite sides of the shaft 33.

20 The casing 30 is provided at one side with an elongated tubular portion 38 extending horizontally at right angles to the governor valve

shaft 33 and having an opening 38 to permit insertion of this shaft, the opening being closed by a plug or cover plate 40. An axial bore 41 formed in the tubular casing portion 38 intersects the opening 38 and provides a slidable fit for an operating rod 42 extending therethrough and into the diaphragm housing 29 which is disposed at an end of the casing portion 38. A guide bushing 43 for the rod is fixedly secured in the same end of the tubular portion, as by a press fit and a locking pin 44. The operating rod 42 is provided with an annularly grooved portion forming rack teeth 45 meshing with the governor shaft pinion 35 for rotating this shaft when the rod is axially shifted. The diaphragm housing 29 is formed by opposed dished members 46 and 47, such as of sheet metal, the former being rigidly secured to the end of the tubular casing portion 38 and the latter having a central fitting 48 to which the conduit 28 is connected. A laminated flexible diaphragm 49 is clamped at its periphery between the dished members 46 and 47, as by bolts 50, and the movable central portion of the diaphragm is clamped between washers 51 and 52 secured together, as by a central screw 53, the end of the operating rod 42 being adapted to abut against the adjacent washer 51. The diaphragm 49 forms a partition between two chambers 54 and 55, Fig. 2, the chamber 54 being in communication with the pressure generator 16 and filled with the hydraulic fluid, and the housing member 47 being provided with a closure screw 56, Fig. 1, to facilitate complete filling of this chamber. The chamber 55 is a vacuum chamber and is in communication with the intake manifold, as hereinafter described, for urging the operating rod 42 in valve-closing direction, as does the hydraulic pressure in the chamber 54.

The axial displacement of the operating rod 42 under fluid pressure is yieldably resisted by a spring unit 57, Figs. 2 and 4, which is disposed in a longitudinal bore 58 formed in the end of the tubular portion 38 of the casing 30 remote from the diaphragm housing. The spring unit includes a cylindrical barrel 59 removably fitting in the bore 58 and abutting at its inner end against an annular stop shoulder 60 formed in the casing portion 38. The barrel 59 has in-turned abutment flanges 61 and 62 at opposite ends and has a pair of bores 63 and 64, the latter being larger than the former, presenting at their junction an annular stop shoulder 65 which is near the inner end of the barrel. A light coiled compression spring 66 is housed in the bore 63 and a heavy coiled compression spring 67 is housed in the bore 64. The adjacent end of the operating rod 42 bears on one face of a marginally flanged disk 68 which slidably fits in the barrel bore 63 and forms at its other face a seat for the inner end of the light spring 66, the in-turned barrel end flange 61 forming a stop for the disk. The outer end of the light spring 66 bears against a marginally flanged spring seat member 69 which is movable in the large bore 64 of the barrel and is adapted to abut against the annular stop shoulder 65, the seat member 69 having a cylindrical extension 70 adapted to be engaged by the disk 68, as seen in Fig. 2. The heavy spring 67 abuts at its inner end on the outer side of the spring seat member 69 and at its outer end against a marginally flanged seat disk 71 which is confined by the in-turned barrel flange 62 to maintain a predetermined minimum compression of the spring. The bar-

rel flange 62 is suitably formed, as by spinning inwardly the end of the barrel after the springs and seat members are inserted. The spring unit is retained in position by a screw plug 72 engaged in a screw thread 73 formed in the outer end of the bore 58, the plug having a reduced cylindrical inner extension 74 which bears against the outer face of the spring seat disk 71. The screw plug has a tool-receiving cross slot 75 which is also adapted to receive a suitable seal 76, Fig. 1, passing through radial openings 77 formed in the casing portion 38. The screw plug may be used to increase the compression of the heavy spring beyond its preset compression.

15 The governor valve shaft 33 has an axial bore 78, Figs. 2 and 5, communicating at its inner end with a small diameter diagonal bore 79 opening at the periphery of the valve shaft in the fuel passage 32 of the governor casing. The operating rod 42 has a sufficiently loose fit in the bore 41 to provide an air passage, and if desired the rod may have a flat 80 to enlarge the passage. By these various passages the diaphragm chamber 55 is placed under a vacuum or low pressure which varies with the intake manifold pressure. The shaft opening 79 is so located that a vacuum in the chamber 55 is prevented or limited until the engine becomes self-operating, as hereinafter described. In addition to the shaft passage 78, 20 79 the governor casing is in some instances provided with one or more additional small diameter air passages 81, Fig. 5, leading from the opening 39 to the fuel passage 32 and controlled by respective needle valves 82 to adjust the effective size of the small passages, the needle valves preferably being inaccessible after the governor casing is installed, so as to prevent tampering.

When the engine is at rest, the governor valve 36 is in the position shown in Fig. 1 where it is held by the then expanded coiled spring 66, the governor valve closing the fuel passageway 32. Preferably, the extent of valve closure is such as to permit the engine to run at idling speed. In this position of the governor valve, the operating rod 42 has been shifted to the left of the position shown in Fig. 2 to a point where the spring disk 68 engages the stop flange 61, as seen in Fig. 4. The opening 79 in the valve shaft 33 is then at the upper side of the shaft and away from the intake manifold.

As the engine is started and comes up to speed, the pressure in the impeller chamber 23 is transmitted through the conduit 28 to the diaphragm chamber 54, urging the diaphragm to the right, 55 as viewed in Fig. 2, and moving the abutting operating rod 42 to the right against the pressure of the light spring 66. The liquid pressure developed at idling speed will move the valve into its fully open position, in this case an approximately vertical position. In this position of the operating rod the spring seat disk 68 abuts against the extension 70 of the seat member 69 for the heavy spring 67. The engine speed may be increased somewhat beyond idling speed without causing further movement of the governor valve because of the resistance of the compressed coiled spring 67. As the engine speed is further increased, the operating rod 52 moves further to the right, as viewed in Fig. 2, by the increasing liquid pressure on the diaphragm, compressing the spring 67 and turning the governor valve 36 through a further angle toward the position shown in Fig. 5. The effective pressure on the diaphragm is then increased by the application 70 75 of intake manifold suction on the diaphragm.

With the two-stage spring reaction against movement of the diaphragm, the governor valve can be easily and quickly moved to its full open position upon initial acceleration of the engine, but the valve will move from its full open position to a restricting position only under considerable pressure in excess of that required initially to move it.

As the speed of the engine tends to increase beyond a point determined by the pressure of the spring 67, the liquid pressure on the diaphragm will increase, thus immediately moving the governor valve to restricting position and limiting the speed. If the engine load is suddenly reduced at the governed speed, the engine will tend to speed up but the governor valve will be quickly moved to its proper speed-limiting position by the control exerted on the diaphragm incident to a corresponding increase in intake manifold suction, thus preventing or minimizing increase of speed. A sudden increase in engine load will tend to reduce the engine speed, but the reduction in intake manifold suction will cause a quick movement of the diaphragm in valve-opening direction, thus preventing or minimizing a drop in engine speed. Hunting or surging of the governor by changes in manifold pressure is effectively prevented by the damping effect of the liquid in the diaphragm chamber 54.

The speed setting of the governor may be increased by screwing in the plug 72, or by removing the spring unit 57 and substituting another spring unit with a different preset spring compression.

The governor is reliable in operation and is of such character as to discourage tampering by operators. If the pump drive should be placed out of action, or if the fluid conduit 23 should be disconnected, then the engine can be started but will not run faster than idling speed or some slightly higher speed, as the governor valve will remain in nearly closed position.

In the modified form of governor shown in Fig. 6, the compressed spring unit of Fig. 2 is replaced by a single compressed coiled spring 67 which is interposed between a spring seat member 69' and a screw plug 72'. The seat member 69' is secured to the end of the operating rod 42, as by a screw 83, a spacer 84 being provided in some instances. The spacer 84 (or the seat member 69' when the spacer is omitted) is adapted to abut against the casing shoulder 61 to limit the spring-urged travel of the operating rod to a position in which the valve 36 is fully open. As in the governor of Fig. 2, the valve is moved to speed-restricting position by hydraulic pressure, modified by intake manifold pressure when very close speed regulation is desired. The construction and operation of the governor of Fig. 6 is otherwise similar to that of Fig. 2.

While the governor of the invention is particularly suitable for vehicle engines it can also be applied to engines for stationary service.

What I claim as new and desire to secure by Letters Patent is:

1. A governor for an internal combustion engine having an intake, comprising a governor throttle valve movable to open and closed position and being in closed position when the engine is at rest, means responsive to engine speed for actuating said valve first to open position upon attainment of a relatively low engine speed and for actuating said valve toward closed position upon further increase of engine speed, resilient means for opposing the movement of said valve

by said speed responsive means and for restoring said valve to closed position when the engine comes to rest, and means responsive to intake pressure for modifying the movement of said valve.

2. A governor for an internal combustion engine having an intake, comprising a governor throttle valve movable to open and closed position and being in closed position when the engine is at rest, means responsive to engine speed for actuating said valve first to open position upon attainment of a relatively low engine speed and for actuating said valve toward closed position upon further increase of engine speed, resilient means for opposing the movement of said valve by said speed responsive means and for restoring said valve to closed position when the engine comes to rest, means responsive to intake pressure for modifying the movement of said valve, and means for preventing actuation of said valve by intake pressure until said valve has been initially opened by said first-named speed-responsive actuating means.

3. A governor for an internal combustion engine having an intake, comprising means responsive to engine speed for developing a fluid pressure increasing with engine speed, a governor valve for the engine movable to open and closed position, fluid pressure actuated means for moving said valve from closed position to open position upon attainment of a predetermined fluid pressure and for moving said valve from open position toward a closed position upon a further increase of fluid pressure, and means responsive to intake manifold pressure for modifying the governing movement of the valve.

4. A governor for an internal combustion engine having an intake, comprising a governor valve for the engine, fluid pressure means responsive to engine speed for moving the valve toward closed position on an increase of engine speed, and means controlled by intake pressure for modifying the movement of said valve.

5. A governor for an internal combustion engine having an intake, comprising a governor valve for the engine, fluid pressure means responsive to engine speed for moving the valve toward closed position on an increase of engine speed, said means including a diaphragm 50 against which the fluid pressure is exerted, and means for subjecting the other side of said diaphragm to intake pressure for modifying the movement of said valve.

6. A governor for an internal combustion engine having an intake, comprising a governor valve for the engine, liquid pressure means responsive to engine speed for moving the valve toward closed position on an increase of engine speed, said means including a diaphragm 60 which the liquid pressure is exerted, and means for subjecting the other side of said diaphragm to intake pressure for modifying the movement of said valve, the mass of liquid at said diaphragm damping the movement of said diaphragm caused by variations in intake pressure.

7. A governor for an internal combustion engine having an intake, comprising a governor valve for the engine, fluid pressure means responsive to engine speed for moving the valve toward closed position on an increase of engine speed, said means including a pressure chamber and a movable element one side of which forms a wall of said chamber, and means 70 for subjecting the other side of said movable

element to intake pressure for modifying the movement of said valve.

8. A governor for an internal combustion engine having an intake, comprising a governor valve for the engine, a casing having a pair of fluid pressure chambers one of which is adapted to be subjected to a fluid pressure variable with engine speed and the other to intake pressure, and an actuator for said valve responsive to the pressures in both of said chambers.

9. A governor for an internal combustion engine having an intake, comprising a governor valve for the engine, fluid pressure means for actuating said valve toward closed position and adapted to respond conjointly to engine speed and to intake pressure, said means including a

reciprocating operating rod, spring means for urging said rod in valve opening direction, and stop means for limiting the spring-urged movement of said rod to a position in which said valve is substantially in full open position.
